H. NYSTUEN

CAN WASHER AND STERILIZER

Filed Oct. 1, 1925

Henry Nysteen

By Walter F. Stabrook
his Attorney

UNITED STATES PATENT OFFICE.

HENRY NYSTUEN, OF HANCOCK, MINNESOTA.

CAN WASHER AND STERILIZER.

Application filed October 1, 1925. Serial No. 59,936.

This invention relates to an improvement in can washers and sterilizers; and it is an object of this invention to provide an apparatus which may be constructed and operated at a low cost, and adaptable for use in communities where the milk and cream are shipped from a central station.

The invention consists of a rotary support for an inverted milk or cream can; a combined hot water and air heater, which is associated with the support for the can by a suitable piping for delivering successively under pressure hot water, vapor and hot air to the can being treated, for washing, sterilizing and drying the can.

The invention consists of certain novel features of construction and combination of parts which will be hereinafter described.

In the accompanying drawings:
20 Figure 1 is a view partly in vertical section and in elevation of the apparatus,

Figure 2 is a vertical sectional view showing a spring controlled valve carried by the piston.

25 In the drawings, the heater 10 is provided with a central horizontal partition 11, dividing the heater into a boiler or hot water chamber 12, and a combustion chamber 13. The water in the boiler or chamber 12 may be connected with a suitable water supply and is heated by an oil burner 14.

30 A drum 15 is located in the chamber 12 and supported on the partition 11. The bottom of the drum 15 is open and communicates with the chamber 13. A chimney 15' on the burner 14, of a smaller diameter than the drum, preferably extends into the lower end of the drum for conducting the heated air to the drum. Connected to the upper end 35 of the drum is a pipe 16 through which the heated air is discharged. A screen 16' is fitted into the pipe at its lower end where the pipe joins the drum for preventing soot and other foreign matter entering the pipe.

40 A valve 20 is applied to the pipe 16 for controlling the discharge of heated air therethrough.

The boiler or water chamber 12 is preferably only partially filled with water to a level indicated by the line 17 for forming a chamber above the water level for the accumulation of heated vapor that may be drawn from the boiler by a pipe 18, controlled by a valve 19.

45 A pipe 21 for withdrawing the hot water from the boiler or chamber 12, is provided

with a valve 22 for controlling the discharge of water from the chamber 13. A pipe 23 to which the pipes 16 and 18 are connected is joined to the pipe 21 by a T-coupling 24, 60 and is provided with a check valve 25 near its lower end to prevent the return of any liquid or gas to the pipes 16 and 18.

55 Mounted on the pedestal 26 is a pump cylinder 27 in which is mounted a reciprocating piston or plunger 28. The piston 28 is provided with a piston rod 29 having rack teeth 29' thereon that mesh with a gear 30, mounted on the shaft 31 journaled on the upper end of the cylinder 27.

70 Extending through the piston rod 29 is a valve stem 50, having a valve 51 at the lower end thereof and seated on the face of the piston 28. The valve stem 50 extends through the upper end of the piston and is 75 provided with a knob 52 for actuating the valve 51. A spring 53 is interposed between the upper end of the piston rod 29 and knob 52 for normally holding the valve 51 seated.

75 A pedestal 32 has mounted thereon a cylinder 33; supported on the upper end of the cylinder 33 is a gear housing 34. A can support or receptacle 35 is rotatably mounted on the gear housing 34. An opening 37 is formed in the bottom of the receptacle 35 80 forming communication with the gear housing 34 and cylinder 33. An outlet spout 38 is connected to the upper end of the pedestal 32 or bottom of the cylinder 33 for carrying off the water discharged from the receptacle 35.

85 A beveled ring gear 39 is connected to the bottom of the receptacle 35, around the opening 37, and is located beneath an annular flange 40, formed on the gear housing for 90 securely holding the receptacle in place. A bevel gear 41 mounted on the shaft 31 meshes with the ring 39 so that upon the rotation of the shaft 31 by the handle or crank 42 the piston 28 is operated and the receptacle 35 100 rotated.

95 A pipe 43 connected to the T-coupling 24 is provided with a check valve 44, and leads to the pedestal 26 and bottom of the pump cylinder 27, for conducting water, hot air or vapor to the cylinder. Another pipe 45 leads from the opposite side of the pedestal 26 and cylinder 27 to the pedestal 32 and upwardly through the cylinder 33 and receptacle 35. The pipe 45 extends at a sufficient 110 elevation above the receptacle 35 to discharge the water, air or vapor into the inverted can

46 supported in the receptacle 35. A suitable nozzle 47 is applied to the end of the pipe for spraying the cleansing agent into the can. A check valve 48 is applied to the 5 pipe 45 beneath the nozzle 47 so that the agent delivered to the can will not be drawn back into the pipe upon the reverse operation of the piston 28.

A can to be washed and sterilized is inverted and placed in the receptacle 35, the valve 22 opened allowing hot water to be drawn into the cylinder 27 upon the rotation of the crank 42, raising the piston in the cylinder 27. After sufficient water has been drawn 10 into the cylinder the crank 42 is operated, reversing the direction of movement of the piston 28 causing the hot water to be conducted through the pipe 45 and discharged through the nozzle 47 for washing the can 46. During the movement of the piston 28 in either direction, the can 46 and receptacle 35 are given a rotation in one direction and then in reverse, so that the inner surface of the can in its rotation is being subjected to 15 sprays of water for cleansing. The check valve 44 prevents the water from returning to the boiler or chamber 12 when it is being ejected from the cylinder 27.

Upon the completion of this operation the 20 operator closes valve 22, and opens valve 19, thereby allowing the hot vapor in the boiler to be delivered to the can 46. The hot vapor is delivered to the pump cylinder 27 through the pipes 23 and 43. When this operation has been performed valve 19 is closed and 25 valve 20 is opened for delivering hot air to the can upon the operation of the pump for drying the can.

In operating the pump, it may be advisable 30 to control the admission of water or other agent to the cylinder 27, and under such conditions, the operator will press down the knob 52 unseating the valve 51, thereby admitting air to the cylinder through the 35 piston and releasing the suction of the piston in drawing the cleansing agent into the cylinder 27. When the piston 28 is moved to eject the water the valve 51 is again closed and the air admitted into the cylinder will be 40 compressed in forcing the water from the cylinder with greater force.

From the foregoing it will be seen that an 45 apparatus has been provided for washing a can subjecting it to hot vapor after washing, and then drying the same by hot air. There 50

are three independent operations wherein the same apparatus is employed and the different agents for performing the function of washing, sterilizing and drying may be delivered independently. 55

Having described my invention, what I 60 claim as new and desire to secure by Letters Patent is:

1. In a can washing and sterilizing apparatus, the combination of a rotary can receptacle, a pump, means for conducting a cleansing agent from the pump to the can, and means connected to the can receptacle and pump for simultaneously actuating the pump and can receptacle. 65

2. In a can washing and sterilizing apparatus, the combination of a hollow support, a receptacle rotatably mounted on the support for receiving an inverted can to be cleansed, said receptacle having an opening for forming a discharge passage to the hollow support, means for conducting cleansing and drying agents to the can, and means for delivering the cleansing and drying agents to the can receptacle through the conducting means under pressure, said means being connected to the can receptacle for rotating the receptacle. 70

3. In a can washing and sterilizing apparatus, the combination of a support, a receptacle rotatably mounted on the support, a gear connected to the receptacle, a pump cylinder and a piston therefor, a power shaft having a gear meshing with the receptacle gear, and means on the shaft for actuating the piston, whereby upon the operation of the power shaft the receptacle will be rotated and the piston reciprocated, and means connected to the pump for delivering a cleansing agent to the can carried by the receptacle. 85

4. In a can washing machine, the combination of a rotary can receptacle, a pump consisting of a cylinder and a reciprocating piston, a pipe connected to the pump cylinder extending through the can receptacle for delivering a cleansing agent to a can carried by the receptacle, and means connected to the can receptacle and to the piston for rotating the can receptacle and reciprocating the piston, and imparting a rotary movement to the can receptacle in one direction on a stroke of the piston and a reverse movement to the can receptacle on the return stroke of the piston. 90
